UNITED STATES PATENT OFFICE.

JAMES FRANCIS BOTTOMLEY, OF WALLSEND, AND ARTHUR PAGET,
OF NORTH CRAY, ENGLAND.

APPARATUS FOR WORKING FUSED SILICA OR THE LIKE.

No. 836,558.

Specification of Letters Patent.

Patented Nov. 20, 1906.

Application filed February 28, 1906. Serial No. 303,551.

To all whom it may concern:

Be it known that we, JAMES FRANCIS BOTTOMLEY, a resident of Wallsend-on-Tyne, in the county of Northumberland, and ARTHUR PAGET, a resident of North Cray, in the county of Kent, England, subjects of His Majesty the King of Great Britain, have invented a certain new and useful Improvement in Apparatus for Working Fused Silica or the Like, of which the following is a specification.

This invention relates to improvements in apparatus particularly adapted for carrying out the process set out in our contemporaneous specification of Letters Patent No. 822,424 of June 5, 1906, for improvements in and connected with the working of fused silica by drawing, blowing, or pressing a plastic cylinder of fused silica formed by fusion of sand or other suitable form of silica round a central core heated by the passage of an electric current. Where "silica" and "fused silica" are hereinafter referred to, the words are intended to cover not only pure silica, but combinations of same or of other materials having melting-points above 1500° centigrade, at which they become plastic and vitreous.

To form the cylinder of plastic silica, we make use of a furnace so constructed as to allow of a separation of the terminals from the heating-core after the completion of the fusion, so that the plastic silica may be removed and the heating-core withdrawn from the cylinder either before or after its removal from the furnace. The heating-core is preferably formed of carbon or graphite and may be either solid or hollow and of any desired cross-section, according to the size and nature of the product required.

In order to allow of the ready withdrawal of the heating-core in the case of a carbon or graphite core, the heating is continued sufficiently to allow of an initial separation between the core and the inner surface of the plastic cylinder, which takes place on account of the formation of a small quantity of gas on the surface of the core.

In case the product is to take the form of a true cylinder special precautions are necessary in order to avoid the tendency to the formation of a D-section. This difficulty may be met by inclosing the material to be heated in such a way as to give uniform support to the plastic cylinder by preventing

any displacement of the material round the core. The amount of current and length of heating may also be regulated so as to prevent the cylinder from becoming too plastic, or the furnace may be rotated on a horizontal axis during fusion. In the alternative the heating-core may be placed vertically, and the furnace may be mounted so as to be reversible. The cylinder, and in consequence the products formed therefrom by drawing or otherwise manipulating during plasticity, are usually rough on the exterior, owing to the imperfect fusion of the outer layer of silica. In order to produce an externally-glazed product, means may be provided either for limiting the amount of material surrounding the core, so that the whole of it is fused, or the rough cylinder may be subsequently treated in a separate furnace, as described hereinafter.

In order to limit the amount of material around the heated core, we may provide a jacket of carbon or other sufficiently-refractory material—as, for example, metals of the platinum group—this jacket being further protected on the outside against heat losses by additional sand or other heat-insulating material. The jacket may be made in two parts, so as to be more easily removable.

Where a cylindrical product is required and a jacket is employed, the vertical form of furnace is preferable, as it facilitates the feeding in of the sand or other form of silica to compensate for the shrinkage in volume during fusion. When the fusion is complete, the plastic cylinder is ready for removal and subsequent treatment. For this purpose the terminals at either end of the heating-core are drawn apart, so as to free the core from the furnace, and one or both ends of the cylinder are clasped by tongs, so that the cylinder may be drawn out and released (if desired) from the jacket or freed from the surrounding sand, the heating-core being withdrawn either before or after the removal of the plastic cylinder from the furnace.

The second furnace may consist, for example, of a tube of carbon or other suitable resistance material fixed between two terminals and heated by the passage of an electric current. The tube is covered with a suitable insulating material to prevent heat losses. For some purposes this may conveniently be of sand, which, owing to the fact that it fuses

round the tube and forms a gas-tight covering for it, affords a good protection against corrosion of the outside of the heating-tube through contact with the air. Nitrogen or other inert gas may be led into the interior of the furnaces for the same purpose.

The second furnace may be either vertical or horizontal and open at one or both ends, according to the purpose for which it is required,

- 10 the vertical arrangement being preferable where a cylindrical product is required, so as to take advantage of gravity. The rotation of the cylinder of plastic material may be employed to insure uniformity of heating and
- 15 also to help in producing a cylindrical product. The manipulation of the plastic cylinder varies with the product required but in every case in which expansion of the plastic mass is required it is necessary to apply sufficient initial force to overcome the external resistance due to external chilling. Where the initial resistance has been overcome, the mass becomes more plastic, so as to be easily expanded.
- 20 25 First. To draw the cylinder, (without blowing,) the cylinder is clasped at both ends by tongs and drawn out. Rotation of the cylinder during drawing may be employed to maintain the cylindrical form, and, if desired, the external jacket, if any, need not be removed prior to the drawing operation.

Second. For blowing the cylinder a nozzle constructed of a material capable of withstanding the high temperature or cooled by

- 30 some device is inserted in one end of the plastic cylinder after withdrawing the heated core and the plastic mass pressed round this nozzle by some suitable means, so as to make a gas-tight joint at this point—e. g., the
- 35 40 pressing may be done by means of tongs which may be conveniently in one piece with the nozzle—and so constructed that by closing the jaws a uniform pressure is exerted on the plastic cylinder round the nozzle. The opposite open end of the cylinder is simultaneously closed by pressure, either by suitably-constructed tongs, which may, if desired, be made to shear off the irregular end produced, or by the end pressure of a suitably-formed die, or both. The cylinder is then removed from the melting-furnace and, where necessary, freed from the surrounding sand, and, where desirable, glazed in the tubular or second furnace before mentioned. Com-
- 45 50 55 pressed air or other gas may be admitted into the plastic mass, which may then be blown out either freely or into a surrounding mold. If desired, the plastic cylinder may be simultaneously drawn while gas-pressure is admitted to the interior of the plastic mass, so as to produce tubing of larger internal diameter or to insure its cylindrical form.
- 60 65 Third. The plastic cylinder may further be compressed between suitable rollers or dies, so as entirely to weld up the interior cavity

and produce a homogeneous mass of any desired form.

Referring now to the drawings, Figures 1 and 2 are longitudinal elevation and plan, respectively, of a furnace in part section adapted for the production of a cylinder of plastic silica and means for separating the terminals and the heating-core from the product after completion of the fusion. Figs. 3 and 4 are longitudinal elevation and plan, respectively, of a furnace in part section capable of being rotated with means for separating the terminals from the fused material when required. Figs. 5 and 6 are longitudinal elevation and plan, respectively, of a furnace in part section capable of being rotated on a horizontal transverse axis into a vertical or horizontal position or of completely reversing, with means for separating the terminals from the fused material and also exemplifying the method of limiting the amount of material by surrounding it with a jacket to produce fusion throughout. Fig. 7 is a longitudinal elevation showing the same furnace rotated into a vertical position.

In Figs. 1 and 2 the heating-core *a* consists of a rod of graphite or hard carbon which fits between the terminals *b* of graphite or carbon. In order to insure the heated core being removed at one end along with the terminal, the rod may be more securely attached to one terminal than to the other. The terminals are held in metal holders *c*, supported on metal stands, to which the current may be led by flexible leads. (Not shown.) The stands are made to slide in insulated transverse guides *d*, while the transverse guides themselves can slide along longitudinal guides *e*. A trough *f* serves as a containing vessel for the material to be fused and may be of any convenient material. The ends *g* of the trough may be made removable, so as to facilitate the manipulation of the plastic cylinder when required.

The following is an example of a method of operation: A graphite rod twenty-four inches long and one inch diameter is fixed between the terminals in the manner described and covered with glassmakers' sand. About one thousand amperes at fifteen volts are passed through the rod for half an hour, when a cylinder of fused silica forms round the core. The fusion being effected, the current is cut off and the terminals drawn back along the longitudinal guides, the graphite core coming out along with the terminal. When the terminals and core are conveniently clear of the furnace, they are pushed along the transverse guides *d* and the plastic cylinder is ready for subsequent manipulation.

The above figures for current, voltage, and length of heating can only be taken as a rough approximation and would vary according to the material of which the heating-core is composed. In order to effect the

withdrawal of the heating-core, it is necessary, however, to carry on the heating sufficiently long to effect the initial separation between the heating-core and fused material 5 by internal generation of gas or to bring about this separation by the introduction of gas or air between the heating-core and the fused material by some device—such as, for example, by using a hollow and perforated 10 core and passing the required quantity of gas through it into the middle of the fused mass, as described in specification No. 812,399 of February 13, 1906.

In Fig. 3 the heating-core *a*, embedded in 15 the material to be fused, is fixed between the terminals *b* in the manner described above. *h* represents metal sleeves through which the electrodes pass. The sleeves are made in two parts, with insulating material *i* between. 20 The flanges on the sleeves form the ends of the chamber *f*, in which the fusion is carried out and are held in position by the wedges *j*. *k* represents metal disks which dip into the mercury-troughs *l*, to which the current is led 25 by means of flexible leads (not shown) and convey the current to the terminals. *m* represents the bearings on which the furnace rotates. By means of the longitudinal and transverse guides *e* the terminals can be 30 drawn clear of the furnaces when required. The chamber *f* itself rotates in the bearings *m*, which support it when the terminals are drawn apart. It is fitted with a cover *o*, which opens on hinges.

35 The method of operation is similar to that described above. For example, current is passed through a heating-core fixed between the terminals until a cylinder of plastic silica of the required dimensions has been formed. 40 During the heating the furnace is kept in slow rotation or rotated from time to time, as desired. The fusion being complete, the current is cut off and the wedges *j* removed, so that the terminals are free. The terminals 45 and heating-core are then separated from the fused material in the manner described above, and after opening up the chamber the plastic silica is ready for further manipulation.

In Fig. 5, *f* is a metal chamber made in two 50 parts. The terminals *b* pass through metal sleeves *h*, which are made in two parts with insulating material *i* between. The flanges on the sleeves form the ends of the chamber and are held in position by the clips *p*. *q* 55 represents trunnions on which the furnace rotates. The sleeves have extension-pieces *r*, which are arranged so that they can engage with the blocks *s*, which run on the transverse guides *d*. Longitudinal guides *e* are also provided, as before. Current is led to the sleeves by means of flexible leads, (not shown;) but if the furnace has to rotate completely brushes or some similar device for conveying the current to the sleeve may be 60 employed.

The method of operation is similar to that described above. The heating is carried out with the furnace in the vertical position, and when complete the furnace is rotated to the horizontal and the extension on the sleeves *h* 70 made to engage with the blocks. The clips *p*, holding the sleeve-flanges at the end of the furnace-casing, are then opened and the terminals drawn apart.

If a material glazed throughout is required, 75 a jacket of carbon or other sufficiently-refractory material may be made to surround the core, so as to limit the amount of material to be fused. The jacket may be used with any of the types of furnace and is shown at *t* in 80 Figs. 5 and 6. The ends of the heating-core may be left unjacketed, if desired, as shown on the right of Fig. 5, in order to facilitate the manipulation of the plastic cylinder, or in order to prevent the material within the jacket 85 from being blown out at the unjacketed ends the ends of the core may be surrounded with a jacket *w* (see Fig. 6) of slightly larger diameter, so that fusion of the outer layer of the contained material does not take place during 90 the main fusion, so that the end jackets are easily removed. One of the extension-jackets may be made funnel-shaped to enable fresh material to be fed in. The jacket may be made in two halves to facilitate its removal 95 afterward, in which case the material surrounding the jacket on the outside, which serves as heat-insulator, may be of some refractory material which does not melt at the required temperature—as, for example, magnesia, carborundum, or the like. In using a 100 jacket it may be advantageous to use a hollow heating-core and terminal and to provide means for regulating the amount of gas given off during the heating. As an example of the 105 method of limiting the amount of material around the heating-core a graphite rod twenty-four inches long and one inch diameter is fixed in position between terminals, with a cylinder of agglomerated carbon three 110 inches internal diameter supported centrally round it, and the whole of the furnace filled with pure glassmakers' sand. One thousand amperes at fifteen volts are passed through until the sand on the exterior of the 115 jacket begins to agglomerate, which occupies about three-quarters of an hour. The furnace is then rotated into a horizontal position and connection made with the arrangement for separating the terminals. The body of 120 the furnace is opened, and after cutting off the current the terminals are separated, and the plastic cylinder contained in the jacket is ready for subsequent manipulation.

According to the alternative method of 125 producing a material glazed throughout the plastic cylinder after removal from the furnace is immediately transferred to an electrically-heated chamber—as, for example, the tubular furnace before mentioned—where it is 130

subjected to radiant heat sufficient to melt the exterior layer of agglomerated material. As soon as the glazing has been effected the plastic cylinder is ready for subsequent manipulation.

By this invention, therefore, we provide a means whereby fused silica, which on account of its high melting-point cannot be worked by the usual processes common to glassmaking—namely, of melting in a receptacle and gathering portions of fused material on a blowing-tube—is brought to such a condition that it can be worked into various articles with comparative ease and while still plastic. Further, the process is one of high thermal efficiency, because, in the first place, practically only the exact amount of material required need be fused and, secondly, because the heat is applied directly to the center of the material to be fused, so that (except in the subsidiary process of glazing) practically no heat is lost in heating the containing vessel.

What is claimed is—

1. In apparatus for working fused silica or the like, a furnace, terminals therein, and a resistance-core so connected thereto as to permit of the removal of the core from the fused mass; so that the fused mass can be removed from the furnace during plasticity, substantially as and for the purposes set forth.

2. In apparatus for working fused silica or the like, a furnace, a jacket therein for limiting the amount of material to be fused, terminals in the furnace and a resistance-core so connected thereto as to permit of the removal of the core from the fused mass within the jacket, and of the fused mass from the furnace during plasticity, substantially as described.

3. In apparatus for working fused silica or the like, a furnace, terminals therein, a resistance-core so connected thereto as to permit of the removal of the core from the fused mass, so that the fused mass can be removed from the furnace during plasticity, and means for rotating the furnace, substantially as described.

In testimony whereof we have hereunto set our hands in the presence of two subscribing witnesses.
